FIG. 1 is a Perspective view of a thermal insulation side
panel showing my new design in close position;

FIG. 2 is a Front view thereof;

FIG. 3 is a Back view thereof;

FIG. 4 is a Right-side view thereof;

FIG. 5 is a Left-side view thereof;

FIG. 6 is a Top view thereof;

FIG. 7 is a Bottom view thereof;

FIG. 8 is a Perspective view of a thermal insulation side
panel showing in open position; and,

FIG. 9 is other back view thereof.

The broken lines in the drawings depict portions of the
thermal insulation side panel that form no part of the claimed
design.
